UNITED STATES PATENT OFFICE.

BENJAMIN A. LEGG, OF COLUMBUS, OHIO, ASSIGNOR TO JOSEPH A. JEFFREY,
OF SAME PLACE.

ELEVATOR.

SPECIFICATION forming part of Letters Patent No. 330,792, dated November 17, 1885.

Application filed April 22, 1885. Serial No. 163,062. (No model.)

To all whom it may concern:

Be it known that I, BENJAMIN A. LEGG, a citizen of the United States, residing at Columbus, in the county of Franklin and State of Ohio, have invented certain new and useful Improvements in Elevators, of which the following is a specification, reference being had therein to the accompanying drawings.

Figure 1 is a side elevation of an elevator embodying my improvements. Fig. 2 is a front view of the same. Fig. 3 is a sectional view of a part of the gearing on a larger scale. Fig. 4 shows the lower end of the elevator. Fig. 5 shows the lower end of the adjusting-screw. Fig. 6 is a horizontal section on line $x x$. Figs. 7 and 8 show the sliding power-shaft. Fig. 9 is a sectional view of the parts at the upper end of the screw. Fig. 10 is a side view of the elevator-frame. Fig. 11 shows 20 a modification of the parts in Fig. 6, and Fig. 12 a modification of those in Fig. 5.

In the drawings the elevator is shown as having a stationary frame consisting of the front uprights, A A, rear uprights, B B, bottom sills, A' A', top sills, A² A², and intermediate sills, A³.

The elevator proper consists of a chain or chains, B', carrying buckets B², the chains engaging with wheels B³ at the top and wheels 30 B⁴ at the bottom.

C is the shaft at the top, which carries the upper wheels, and C' the bottom shaft for the wheels B⁴. These latter parts are supported in an adjustable frame having side pieces and 35 as many cross-bars as are necessary.

As shown, the side parts are constructed of bars D D', at top and bottom, connected by two bars, D² D². These latter are so arranged, as will be seen, as to leave a passage-way between 40 them for a purpose to be described, there being one of these passage-ways on each side of the elevator.

The movable elevator-frame is connected with the stationary frame by means of a shaft, E, which, as shown, is mounted in bearings at e at the upper end of the last said frame, and is made either in sections, as in Fig. 5, or continuous, as in Fig. 12. The connection 45 between the two frames is effected by means of a screw-shaft, F, which is carried by the movable frame and secured thereto by means

of the cross-bars d d', the shaft having collars, which prevent it from moving endwise, but permit it to rotate in the bearings on said cross-bars. At E' there is a nut carried by 55 the shaft E, with which the shaft F engages, it being secured as in Fig. 5 or Fig. 12, or in other suitable way. If the screw-shaft be rotated in one direction or the other, the movable frame will be raised or lowered, as will be more 60 fully hereinafter described.

The devices by which power is imparted to the chains, and also those by which the screw-shaft F is rotated, are constructed and arranged as follows: At H there is an engine, which 65 may be of any preferred form. It drives a wheel, h, which is connected with a wheel, h', by a chain, h². The shaft h³, which carries wheel h', also has a second chain-wheel, h⁴, which is connected by chain h⁵ with a wheel, 70 E², on shaft E. This wheel is loose thereon, and is formed with an elongated hub or sleeve, E³, to the outer end of which is keyed a bevel-pinion, I.

J is a shaft mounted at right angles to the 75 shaft E. At the lower end it is supported in the bracket having arms J' and J², which are provided with a bearing at j for the lower end of the shaft J, and at j' with a bearing for the sleeve E³. The wheel I engages with a bevel-wheel, I', carried by the shaft J. It will be 80 seen that the wheels E² and I will revolve freely independently of the shaft E, and also that the bearing-brackets J' and J² can be swung into any desired position without varying the working relation between the bevel-wheels I and I'.

At the upper end of shaft J there is a bevel-wheel, K, meshing with a wheel, C³, on shaft C, this shaft being extended somewhat beyond the elevator-frame, and 85 mounted in a bracket at c³, carried by another bracket, c⁴, secured to the frame, and which has a bearing at k for the upper end of shaft J. The shaft J is grooved and fitted to a feather or spline carried either by the wheel 90 K or the wheel I', so that said shaft can be moved longitudinally relative to said spline or feather and still have a rotating engagement therewith.

The manner of transmitting the power of 100 the engine to the shaft C will be readily understood from the above description, the work-

ing relation between the engine and the last said parts being constant in whatever position the movable frame is located.

Power is taken from shaft C for the purpose of raising the elevator or lowering it relative to the shaft E as follows:

L is a chain-wheel on said shaft, and L' a similar wheel on a supplemental shaft, l, mounted in the movable frame, there being a chain at l', which unites the wheels L L'.

f is a bevel-wheel on the end of shaft F, and rotated in one direction or the other by the beveled pinions m m'. These are carried by a sleeve, M, joined to shaft l by a feather, and provided with any suitable shipping mechanism. When it is desired to rotate the screw F in such way so as to raise the movable frame, the pinion m is slipped into engagement with wheel f, and when the screw is to be oppositely-rotated the other wheel, m', is brought into engagement. When the shaft F is to remain stationary, the sleeve M is so situated as that neither of the wheels m m' can engage with wheel f. The material which is carried to the top is delivered to one or more chutes, N, which in turn deliver it to diverging chutes N' N''. From these the material passes to carriers O O', each consisting of one or more chains, o, and cross-bars o'. The carrier O delivers material to a hopper, P, from whence it passes to the carrier p, and the carrier O' delivers its material to a similar hopper, P', and carrier p'. The carriers p p' are arranged to run backward either horizontally or somewhat inclined, and they deliver the material to the point ultimately desired. These various carriers may be constructed in any of the now known ways.

Q is the shaft through which power is transmitted to the various carriers above mentioned, O O' p p'. This shaft Q has a wheel, q, joined by a chain, q', with a wheel, Q', on the shaft h'.

R R' are bevel-wheels on shaft Q, one driving the carrier O by a bevel-wheel, S, and the other driving carrier O' by a bevel-wheel, S'. By means of these parts of the mechanism I am enabled to elevate the material from a boat, car, or other receptacle in large buckets and subsequently carry it to the points of ultimate delivery in smaller masses, and therefore effect the unloading of such receptacle very rapidly. At or near the lower end of the movable frame I employ adjustable braces, as shown at T, they being held in guides or other supports carried by the stationary frame. They bear against the side pieces, D', of the movable frame, and are preferably provided with anti-friction rollers t, to avoid any friction when the movable frame is being raised or lowered. At the lower end of the elevator-frame means are provided for protecting the buckets, so that they shall not be pressed with too great force upon the material below, and so that they shall not scrape the bottom of the receptacle which is being unloaded. As shown, these consist of a cross-bar, U, and supporting

bars u, secured to the lower end of the bars D', the cross-bar U lying below the path of the buckets.

70

What I claim is—

1. The combination of the stationary frame, the movable frame, the shaft passing through the movable frame, and the shaft or bar transverse thereto and carried by the movable frame, the two shafts being joined together, substantially as and for the purpose set forth. 75

2. The combination of the stationary frame, the movable frame, the bar or shaft on the stationary frame about which the movable frame 80 swings, the transverse bar or shaft on the movable frame adapted to be connected with the aforesaid bar at various points to hold the movable frame higher or lower, and means for raising and lowering the last said frame, substantially as set forth. 85

3. The combination of the stationary frame, the movable frame, the screw-shaft carried by the movable frame, the nut carried by the stationary frame, and the rotating devices which 90 operate said screw, substantially as set forth.

4. The combination of the stationary frame, the movable frame, the screw-shaft secured to one of said frames, the nut secured to the other and adapted to rock, and the power devices 95 which rotate the screw-shaft, substantially as set forth.

5. The combination of the stationary frame, the movable frame, the screw-shaft about the axis of which the movable frame rocks, the 100 gearing mounted about the axis of the said shaft, and the gearing which drives the elevator connected with the aforesaid gearing, substantially as described.

6. The combination of the stationary frame, 105 the movable frame, the shaft or bar about whose axis the movable frame rocks, the gearing mounted upon said axis, the bracket-frame secured to the movable frame to support said gearing, and the sliding shaft, substantially as 110 set forth.

7. The combination of the stationary frame, the movable frame, the bar or shaft about whose axis the movable frame rocks, a wheel, E'', and a wheel, I, connected together and mounted 115 upon said axis, the sliding shaft driven by wheel I, and a bracket-bearing connected with the movable frame and also with the wheel I and sliding shaft, substantially as set forth.

8. The combination of the stationary frame, 120 the movable frame, the shaft at the end of the elevator which drives the latter, the screw-shaft by which the elevator is adjusted, and the power-transmitting devices interposed between the screw-shaft and said shaft at the 125 end of the elevator, substantially as described.

9. The combination of the stationary frame, the movable frame, the devices which raise and lower the movable frame, the shaft which drives the elevator, and the sliding shaft which 130 imparts power both to the elevator driving-shaft and to the raising and lowering mechanism, substantially as set forth.

10. The combination of the stationary frame,

the sliding frame, the shaft F, shaft l, and the shifting-pinions m m', substantially as set forth.

11. The combination of the stationary frame, the sliding frame, the shaft F, adapted to be connected at different points with the stationary frame, shaft l, shaft C, and transmitting devices between shaft C and shaft l, substantially as set forth.

12. The combination of the stationary frame, the movable frame, the bar or shaft about which the movable frame rocks, the gearing adapted to vibrate about the axis around which the movable frame rocks, the shaft which drives the elevator, and the power-transmitting devices between said gearing and said shaft, substantially as set forth.

13. The combination of the elevator, shaft C, chain l', shaft l, screw-shaft F, and reversible power-transmitting devices interposed between shaft l and shaft F, substantially as set forth.

14. The combination, with the delivery-chute,

of the diverging hoppers or chutes and the endless carriers which withdraw the material therefrom, substantially as set forth.

15. The combination of the elevator, the receiving-chute which takes the material therefrom, the diverging hoppers or chutes, the carriers which respectively take the material therefrom, and the carriers which carry the material backward away from the last aforesaid carriers, substantially as set forth.

16. The combination of the carriers O O', the chute which feeds both of said carriers, the carriers p p', and a wheel, Q', and mechanism interposed between said wheels and carriers whereby it is adapted to drive them all simultaneously, substantially as set forth.

In testimony whereof I affix my signature in presence of two witnesses.
